UNITED STATES PATENT OFFICE

2,126,082

AMUSEMENT DEVICE

John E. Bailey, Los Angeles, Calif.

Application September 24, 1935, Serial No. 41,889

15 Claims. (Cl. 273—45)

This invention relates generally to amusement devices for games such as tenpins in which a plurality of pins are provided for removal from a playing surface by the impact of a ball or other object directed against them by the player, and specifically refers to novel means for restoring the pins to the playing surface at the conclusion of the game.

In tenpins or other games, including bowling, 10 to which the present invention also appertains, objects moved by a propelled ball have heretofore required manual replacement, which increases the cost of playing and involves a loss of time detrimental to the interest of the game.

15 Marble games conducted in public on small playing boards are invariably inclosed under glass to prevent tampering and insure accurate and continued operation. Such requirements of construction have heretofore militated against 20 the adaptation of games of the character herein designated due to lack of practical means to mechanically remove the pins when struck and to maintain control thereof for subsequent replacement at the will of the player.

25 It is a particular object of the present invention to avoid such perplexities of the prior art by the provision of a game of skill having for its object the removal of individual pins from the playing surface by the impact of a ball or shot 30 directed against them and embodying means to enable the player to subsequently restore the pins to their original position on the surface with a minimum of effort.

Another object is to provide a plurality of 35 removable supports for novel forms of tenpins or the like protruding through a playing surface, said supports adapted to be tripped by movement of the pins so as to permit the top of individually-moved pins to be dropped even with the surface, 40 the degree of movement required to trip the supports to be easily regulated, thus permitting variation in the amount of skill required by the player to accomplish the removal of any or special pins.

45 Another object is to provide a support for a pin which may be removed by the impact of an object against any point on the periphery thereof thus permitting the pin to be dropped either by a direct hit or by impact caused, for 50 instance, by the rebound of the object from another pin.

Still another object is to provide a device in which pins of any design, or arranged in any configuration may be employed, and which embodies simplicity of construction, facility of oper-

ation, durability, and economy of manufacture.

In the drawing—

Fig. 1 is a perspective view, partially cut away, of a playing board illustrating relative positions of a series of pins projecting therethrough; 5

Fig. 2 is a detailed sectional view, partly in elevation of the means of my invention, illustrating a pair of pins in relatively supported and dropped positions;

Fig. 3 is a sectional view on lines 3—3 of 10 Fig. 2;

Fig. 4 is a view taken on line 4—4 of Fig. 3;

Fig. 5 is an enlarged view of the tripping mechanism for releasably supporting the pin;

Fig. 6 is a sectional view of the parts hereof 15 illustrated in Fig. 2 as relatively moved to restore a dropped pin to the surface of the board.

Referring to the drawing in detail, the numerals of which indicate similar parts throughout the several views, 10 designates a portion of 20 a playing board of a tenpin marble game having supporting walls 11. Ten holes 12 in board 10 are spaced in any suitable relation, preferably in the form of an equilateral triangle with one of its bases parallel with the back of the board. 25 In each hole 12 a tenpin 13 is supported by means about to be described, extending above the board so as to have the appearance of setting on the surface thereof. The pins 13 may incorporate any specific design but are preferably provided 30 with a flat top 14 at their upper ends to substantially fill holes 12 when in their lower position, and a flange 15 at the lower end of each pin, slightly smaller than the diameter of top 14 to permit the pin to tilt in any direction upon 35 being struck.

The lower end of each pin is conically bored and has a hole in the center thereof provided with a lining 16, said lining being thicker at its inner end so as to reduce the diameter of the bore 40 17 of the hole. The flange 15 of each pin is bound in a metal ring 18 which conforms to the shape of the hole 12 to reinforce the pin against abrasion and fracture while raising and dropping, as well as to weight the lower end to facilitate 45 maintenance of the pin in an upright position.

Spaced below, and parallel with, board 10 a distance slightly less than the length of pin 13, a plate 19 is provided, being bolted on a series of supporting bars 20, secured by any suitable means 50 to a bottom board 21, later referred to.

Plate 19 provides support for the pin when the same is dropped through hole 12, so that the top 14 of a dropped pin is flush with the playing surface 10. Secured to the underside of the 55

board 10 around each hole, by screws, rivets, or the like, in a manner well known in the art, is a circular guide 22 which extends downwardly to plate 19 to prevent displacement of pins 13 when the same are dropped, as will appear.

Vertical support and movement of each pin is accomplished by a rod 23 adapted to extend from below plate 19, through a hole therein, into the bore of lining 16 in each of the pins. Rod 23 is annularly beveled at 24 to facilitate its introduction into the bore of the pins, and particularly into the reduced inner bore of lining 16, which frictionally engages rod 23 to releasably maintain the rod and pin in axial alignment.

15 A plurality of rods 25 secured to bottom casing board 21 by nut 26, directly below the vertical axis of pin 13, provide support for the lower end of rods 23 when the pins assume their position above the surface of the playing board 10. The lower 20 end of a helical wire spring 27 encircling each rod 23 extends through a hole, spaced between the ends of the rod so as to compress the spring against plate 19 when rod 23 is supported on rods 25, and respective pins are in position above the 25 board 10.

Plate 19, through which rod 23 passes, acts as a fulcrum to enable a slight impact of the ball or shot, usually employed in such games, against pin 13 to dislodge the lower end of rod 30 23 from the small area of its supporting contact on rod 25 and permit pin 13 and rod 23 to drop. The expansibility of spring 27 will, by jerking the rod downwardly, free the upper end of said rod from the narrow portion of the bore in pin 13 and 35 into the enlarged bore in the lower part thereof, which allows the rod to tilt slightly with respect to the vertical, permitting its opposite end to slide by rod 25. Rod 23 is prevented from dropping through the hole in plate 19 by a fid 28 extending 40 through the rod above plate 19. It will thus be seen that any one tenpin may be dropped from the surface of the board by the player without disturbing the position of the others, and that the pins must be individually struck to be dropped.

45 All pins successfully dropped may be restored to their original position above the board by means comprising a plate 29 provided with a series of holes corresponding to the position of rods 25 and bars 20 to permit the plate 29 to be slidably raised 50 and lowered thereon. The extent of the upward movement of plate 29 on each bar 20 is limited by a peg 30 inserted in a hole in each of said bars. Other holes 30a in vertical alignment with peg 30, as illustrated, are provided in said bars, into which 55 pegs 30 may be optionally inserted to permit adjustment in the range of movement of said plate. A round flange 31 is provided between plate 29 and bottom board 21 which limits the lower reach of said plate.

60 A collar indicated at 32 having an upwardly inclined integral funnel 33 at its upper end is provided to slidably encase each rod 25 above plate 29. The raising of plate 29 by means about to be described thus slides each funnel and collar upwardly on its respective rod 25 until the sloping walls of the funnels contact the end of each rod 23 of all pins which have been dropped below board 10. Continued upward movement of plate 29 will cause each dropped rod to be raised from 65 its support on plate 19 by its funnel. As the weight of the rod is transferred to the funnel, augmented by the increasing urge of the compressing spring 27, the end of the rod will tend to slide toward the bore of collar 32. When the plate 29 70 nears the limit of its upward movement, as defined

by peg 30, collar 32 will pass slightly above the upper reach of rod 25 and rod 23 will slide into the bore of collar 32 to position on the lower rod. Fid 28 operates to steady the pin with respect to rod 23 as it is raised to its upper position. The collar and funnel may then be lowered by lowering plate 29, and the pins will have been restored to their original position.

The vertical movement of the plate 29 above described is accomplished by a series of arms 34, 10 one end of which is pivoted to studs 35 located on bottom board 21. A roller 36 provided in the opposite end of each arm 34 is adapted to contact plate 29 when the arm is raised to uniformly convey its upward movement to the plate. 37 15 designates a bowed member located adjacent the side wall 11, and 38 an extension thereof, having their outer ends communicated with the free ends of arms 34 to simultaneously raise the arms by pulling a handle (not shown) at the opposite end 20 of member 37, as will be apparent to those of skill in this art.

It will be seen that I have provided a device in which the force of the impact on the pins above the playing board necessary to drop the pins to 25 their lower position may be decreased by narrowing the arc of contact between the rods 23 and 25, or increased by providing an indentation in the lower supporting rods and pointing the end of the upper rods, as depicted in Fig. 5.

30 While I have illustrated and described but one embodiment of my invention, it will be obvious that various changes may be made, such, for instance, as in the means for raising the plate 29, the design, proportion and arrangement of the 35 parts, without departing from the essence of my invention; and in specific designs hazards may be formed in the board as the play proceeds by placing plate 19 lower relative to board 10 to permit each pin to drop clear of hole 12; or additional 40 score may be credited the player by projecting the marbles or shot into the holes thus formed.

What I claim and desire to cover by Letters Patent is:

1. In a device of the character described, a perforated playing board, a rod mounted below said board concentric with said perforation, and a second rod supported by said first rod and adapted to be moved laterally therefrom.

2. In a device of the character described, a 50 perforated playing surface, a stationary vertical rod therebelow, a second rod supported on the end of said vertical rod adapted to project, when so supported, through said perforation above said playing surface, and a fulcrum intermediate the 55 ends of said second rod to permit an impact against its upper end to displace its lower end relative to said stationary rod.

3. In a device of the character described, a 60 perforated playing board, a support directly below said perforation, a rod adapted to rest on said support to extend when so supported through the perforation of said playing board, and a fulcrum for said rod intermediate its ends.

4. In a device of the character described, a 65 perforated playing surface, a stationary vertical rod therebelow, a second rod supported on the end of said vertical rod adapted to project, when so supported, through said perforation above said playing surface, a fulcrum intermediate the 70 ends of said second rod to permit an impact against its upper end to displace its lower end relative to said stationary rod, and a funnel slidably encasing said stationary rod to raise and center said second rod on said stationary rod.

5. In a device of the character described, a perforated playing surface, a plurality of pins each having a rod extending from one end, perpendicularly disposed relative to the board, in said perforation, a support for the lower end of said rod, a fulcrum for said rod between said pin and said support to permit an impact against said pin to remove said rod from said support, and resilient means adapted to facilitate lowering of said rod 10 when removed from said support.

6. In a device of the character described, a pin having a bore in its lower end, a rod adapted to be inserted in the bore of said pin to maintain said rod, when so inserted, in axial alignment 15 with said pin, and a support for the opposite end of said rod in axial alignment with said pin, adapted to permit relative lateral displacement of the rod by tilting the pin.

7. In a device of the character described, a rod, 20 a pin having a bore in its lower end adapted to maintain said rod, when inserted therein, in axial alignment with said pin, a support for the opposite end of said rod in axial alignment with said pin, means to withdraw said rod from the bore of said pin to enable said rod to be tilted with respect to the axis of said pin, a fulcrum for said rod to permit an impact against said pin to displace the opposite end of said rod with respect to said support and means to return said 25 rod to position on said support.

8. In a device of the character described, a perforated playing surface, a pin, means to support said pin on the plane of said playing surface above the perforation therein, a stationary support 30 in vertical alignment with said pin to support said means so as to permit the pin to drop through said perforation when tilted, and a flange at the top of the pin to substantially close the perforation in said playing surface when the pin 35 is in its lower position.

9. In a device of the character described, a perforated playing surface, a pin, means to support said pin on the plane of said playing surface above the perforation therein, a stationary support 40 in vertical alignment with said pin to support said means so as to permit the pin to drop through said perforation when tilted, a plate to support said pin with its upper end flush with the level of the playing surface when the same is 45 dropped, and a flange at the top of the pin to substantially close the perforation in said playing surface when the pin is in its lower position.

10. In a device of the character described, a pin, a hole in the lower end of said pin, the inner 50 portion of said hole having a smaller diameter than the outer portion of said hole, a rod having

a diameter substantially equal to the inner portion of said hole to maintain said rod and pin in axial alignment, means to withdraw said rod from the inner portion of said hole, and means 5 to prevent withdrawal of said rod from the outer portion of said hole.

11. In a device of the character described, a pin having a hole therein, a rod extending into said hole whereby the pin and rod are normally maintained in axial alignment so that tilting of 10 the pin will tilt the rod, a support for said rod and pin in vertical alignment therewith, and a fulcrum intermediate the ends of said rod so that an impact against the pin will tilt the rod and remove the lower end thereof from said support. 15

12. In a device of the character described, a pair of pins, a rod extending into a hole in each of said pins, a support for the opposite end of each of said rods, said rods and pin being adapted to be removed from said support by tilting of 20 said pins and rods to permit said pins to drop to a lower position, a funnel below each of the lower ends of said rods, in vertical alignment with respective pins, and means to raise all of said funnels to raise and center said rods on respective 25 supports.

13. In a device of the character described, a pin, means to support said pin, a stationary support in vertical alignment with said pin for the support of said means, and a fulcrum intermediate 30 the ends of said means so that an impact against the upper end of said means will dislodge the lower end with respect to said stationary support.

14. In a device of the character described, a perforated playing surface, a pin, means to normally support said pin on the plane of said playing surface above the perforation therein, a support for said pin below said playing surface, a stationary support for said means in vertical alignment with said pin so that an impact against 35 the upper end of said means will dislodge the lower end thereof and permit the pin to drop, a funnel to engage the lower projection of said means, and means to raise said funnel so as to return said first-mentioned means and the pin 40 to its original position on said stationary support. 45

15. In a device of the character described, a pin, a support below said pin, connecting means normally disposed between said pin and said support but adapted for removal from said support by lateral pressure against said pin, and means comprising a funnel-shaped cup slidably connected with said support to urge said connecting means to its normal position between said pin and said support. 50

JOHN E. BAILEY.
